UNITED STATES PATENT OFFICE.

ALBERT G. THOMAS, OF LYNCHBURG, VIRGINIA.

CABINET FOR DISK RECORDS.

1,289,961.

Specification of Letters Patent. Patented Dec. 31, 1918.

Application filed September 9, 1918. Serial No. 253,172.

To all whom it may concern:

Be it known that I, ALBERT G. THOMAS, a citizen of the United States, residing at Lynchburg, in the county of Campbell and

5 State of Virginia, have invented certain new and useful Improvements in Cabinets for Disk Records, of which the following is a specification.

My invention relates to cabinets for holding and delivering disk-records.

The objects of the invention are to provide a cabinet for disk-records in which the records may be listed in definite order and in which any record may be easily and 15 quickly removed when wanted and no other record may be removed from the cabinet until the one previously removed has been replaced; to provide such a cabinet with a novel form of record ejecting mechanism; to 20 provide means for automatically locking the ejector after every operation; to provide a novel mechanism for preventing the removal of all records save the one in the path of the ejector and to provide novel means to obviate the necessity of using dummy records 25 or blanks; to provide a novel means for closing the record receiving spaces except that for the record being used.

These objects I accomplish by the mechanism shown in the accompanying drawings in which:

Figure 1 is a front elevation of my improved cabinet part of the casing being broken away.

Fig. 2 is a horizontal section of same on line 2—2 Fig. 3.

Fig. 3 is a central vertical transverse section.

Fig. 4 is a perspective of the record-actuating and controlling mechanism removed.

The case or cabinet is designated by the letter L, and may be of any suitable material and design. As shown the cabinet is formed of upper and lower sections, the upper 45 per section being adapted for records of a size smaller than those to be received in the lower section. The front of the cabinet is inclined and provided with upper and lower series of vertical, parallel record-receiving 50 slots L', the upper and lower ends of which slots register with the outer ends of the rearwardly and downwardly inclined grooves J, K, in the top and bottom boards J', K',

beyond which are arranged the stop bars M, M, against which the rear edges of the records rest at the end of their inward movement down the inclined channels.

Above the top boards J' extend the parallel horizontal guide rods E, E, the ends of which are secured in the ends of the cabinet L. Upon these rods are mounted the ejector mechanisms each comprising a slide A, movable across the line of records and provided at its outer end with a finger-piece A' extending through a slot L² in the front of the cabinet. To the rear end of the slide A, is pivoted the slotted upper end b of a depending ejector-lever B, adapted to swing into a vertical position by gravity and also adapted to be swung forwardly or outwardly at its lower end by means of a spring-retracted actuating rod C. This rod C, is mounted slidingly near its rear end in a bracket c on the under side of the slide A and extends at its outer end through an aperture a² in the slide A and terminates at its outer end in a finger-piece c'. The rod C, is retracted by means of a coil spring c², secured at its rear end to the bracket c and secured at its forward end to the rod C so that when the rod is pulled out and released the spring c² will pull it back. The rear end of the rod C, extends through the slot b, in the upper end of lever B, and is provided with a cross piece c³ clamped between two nuts c⁴, this cross piece serving, when the rod C is pulled out, to throw the lower end of lever B outwardly or forwardly. The upper rear side of the lever B, is provided with a pawl or tooth F, adapted to engage any one of a series of notches in a rack bar H secured to the rear wall of the cabinet. The notches in the rack H, coincide or register with the grooves J, K, and hence with the rear edges of the records R. It follows therefore that when the rod C, has been made to pull the lever B, forward to eject a record, the lever will be moved to the vertical and its pawl F, will engage the rack bar and lock the slide A against movement along the rods E, and in consequence of such locking there can be no movement of the ejecting mechanism to another record until the record has been replaced in the grooves from which it was ejected. When this takes place the record will strike the lever B, and move its pawl

out of engagement with the rack H, as shown in lower part of Fig. 3; the upper part of said figure showing the lever B in its vertical locking position and the record in position for removal.

- The front exposed end of slide A, is provided with a pointer N, to register with marks placed above every slot as shown at 1, 2, 3, &c.; these marks indicating the names of the records. When a particular record is desired the slide A, is moved until the pointer registers with the indicating mark thereof and then the rod C is pulled to cause lever B, to eject the record as before described. The lever B, is just wide enough to reach from one record to another so that when the slide A, is moved the lever B, will be slid across the rear edges of the record and will not fall between any two of them, but lever B, is not wide enough to engage the next record when its vertical center engages the one to be ejected. It will be understood that blank records or dummies will be placed in any spaces not occupied by record disks so that the lever B, cannot drop and lock the slide A, owing to unfilled spaces. The blanks also prevent a record from being placed in any but its proper compartment.
- To avoid the necessity of using blank records the following mechanism is provided. Depending from the forward portion of the slide A, are two parallel vertical rods A⁴, spaced apart the width of a slot L' so that a single record may be inserted between them into the grooves J, K, and to the lower ends of these rods A⁴, are secured the ends of a flexible strand A⁵, which extends across the middle portions of all of the slots L', not in register with the space between said rods A⁴. This strand A⁵ is guided on four pulleys a⁶ within the four corners of the cabinet. This strand in other words closes all of the slots L', except the one from which the record has been removed or is to be removed and may be formed of a cord, tape or chain, as may be desired. By thus closing or barring the entrance of disks to any but the one from which a disk has been removed the removed disk must be replaced in the proper channel or space and so will return lever B, to its normal unlocked position. Lever B, cannot be pulled forward when resting on two records as at that time pawl F, will be out of register with a notch in the rack H. The rods A⁴, travel in spaces j, between the slotted front L' and the outer edges of the top boards J.
- To limit the movement of the slide A, along the rods E, E, so that the lever B, cannot be brought past those grooves containing consecutively arranged records I provide sliding collars P, on the front rods E, at opposite sides of slide A, and these

rods are held by set screws p. For instance, should the middle portion only of the cabinet be filled with records the collars P will be set so that the slide A, cannot be moved far enough to carry lever B, beyond the end 70 records. The spaces filled must always be consecutively filled either with records or with blanks though all of the entire series of spaces need not be filled.

This filling of all of the spaces, as far 75 as used, consecutively, is to prevent the lever B, falling into an unfilled space and so locking the slide until B, is released by inserting a record.

The distance between the upper and lower 80 grooves J, K, will be sufficient to allow for slight variance in the diameter of records.

Briefly the operation is as follows: The slide A, is moved along until its pointer registers with the indicating name or mark 85 of the desired record. Rod C, is then pulled forward which causes the record to be ejected or moved outwardly within the grasp of the operator. The rod will now be released and its spring will retract it, thus 90 allowing lever B, to remain vertical with its pawl engaging the rack and locking the slide. The record must be returned to its proper position by reason of the flexible strand A⁵ closing all of the other record receiving spaces. In returning to its position the record will release lever B, from the rack and so the slide and lever may be moved to the next desired record.

While I have shown an upper and a lower 100 series of record receiving channels and ejector devices it is obvious that I may use only one or any desired number.

What I claim is:

1. The combination in a record cabinet 105 having spaces for the records, of an ejector mechanism common to all of said spaces and movable from one record space to any other to eject the records one at a time, the said ejector mechanism being provided with record-controlled means for locking it against a second operation, after the ejection of a record, until the removed record has been replaced to restore the ejector mechanism to its operative position.

2. A record cabinet comprising a series of parallel vertically disposed record-receiving channels or spaces, a record-released ejector mechanism movable transversely across the same and provided with an ejector lever to 120 register with the rear of any desired channel or space and throw the record contained therein forwardly, means for automatically locking the ejector mechanism after the forward throw of the lever and until released by the replacement of the removed record, and means for manually actuating said lever in its forward direction only.

3. A record cabinet having parallel, vertically disposed record-receiving channels or

spaces, an ejector mechanism movable transversely across the same and provided with a combined locking and ejector lever adapted to register with any desired record-receiving space and throw the record forwardly therefrom, means for manually actuating said lever, a pawl or tooth at the upper end of the said lever, and a rack adapted to be engaged by said pawl to lock the ejector mechanism upon removal of a record and again release it upon replacement of the record.

4. A record cabinet having parallel vertically disposed rearwardly-inclined record-receiving channels or spaces, an overlying manually operable slide movable across the same and provided at its rear end with a depending locking lever, the lower portion of which is adapted to be brought into register with the rear end of any desired channel, a manually actuated device carried by the slide for throwing the lever forwardly to eject a record; the lever then acting as a lock for the slide until the replacement of the record.

5. The combination with a cabinet or case provided with a series of vertically disposed parallel, rearwardly-inclined record-receiving channels, a slide movable transversely across the same and provided with an exposed finger-piece, a lever pivoted at its upper end to the rear end of said slide to swing down by gravity, a manually actuated operating rod extending longitudinally of the slide and connected at its rear end to the said lever to swing it forwardly to eject a record and then release it, a pawl or tooth at the rear of the upper end of said lever, a horizontal rack bar having its recesses coinciding with the record-receiving spaces and engaged by said pawl or tooth after the ejection of a record to lock the slide until the record has been replaced.

6. The combination with a cabinet having a series of vertically-disposed, parallel, rearwardly-inclined record-receiving channels, a manually operable slide movable transversely to the said channels, a record-released ejecting gravity lever pivoted to the rear end of said slide and of a width greater than the space separating said channels to prevent its dropping between the records lying in said channels, and so causing it to slide across the rear edges of the records when moved by the slide, until the desired record is reached, manually operable means for throwing the lever in one direction only, to eject a record, means for automatically locking the lever and slide against movement

after the ejection of a record until released by the return movement of the record.

7. The combination with a cabinet having a series of parallel vertically disposed record-receiving channels or spaces, of a transversely movable manually actuated ejector mechanism adapted to be moved across the channels to bring the ejector into register with the rear of the desired channel, record released locking means for preventing transverse movement of the said ejector mechanism until the replacement of a removed record, and adjustable stops at opposite sides of the ejector mechanism to limit its movement to a particular section of the channels.

8. The combination with a cabinet having a series of vertically disposed parallel, rearwardly inclined record-receiving channels open at the front and rear, of guide rods extending across the upper side of the channels, a slide mounted on said rods and having an operating finger piece at the front of the cabinet, a gravity lever pivoted at its upper end to the rear end of said slide, and there provided with a locking pawl, a rack adapted to be engaged by said pawl, an operating rod extending from the front end of the slide to said lever for throwing it forwardly to discharge a record, the lever then swinging to its locking position and means operated by the slide for closing the entrance to the channels other than the one with which the said lever is in register.

9. The combination with a cabinet having parallel channels for the records, of a self-locking record-released ejector mechanism common to all of said channels adapted to be moved into register with any desired channel, automatically locked after the ejection of a record and unlocked by the return of the record, and means for preventing the insertion of a record in any channel save the one from which one has been ejected.

10. The combination with a cabinet having a series of vertically disposed record-receiving channels, indicating marks thereover, a manually actuated slide having a pointer to contact with said indicating marks, a gravity lever at the rear of the slide to eject the record from the selected channel, a manually actuated spring retracted rod carried by said slide and operatively connected at its rear end to said lever to first throw it forwardly, lock it, and then release it; the replacement of the discharged record serving to unlock the lever.

In testimony whereof I affix my signature.

ALBERT G. THOMAS.
